UNITED STATES PATENT OFFICE

122,612

DESIGN FOR AN AUTOMOBILE DEFROSTER FAN BRACKET

William W. Wittie, Chicago, Ill.

Application April 6, 1940, Serial No. 91,523

Term of patent 3½ years

To all whom it may concern:

Be it known that I, William W. Wittie, a citizen of the United States, residing at Chicago, in the county of Cook and State of Illinois, have invented a new, original, and ornamental Design for Automobile Defroster Fan Brackets, of which the following is a specification, reference being had to the accompanying drawing, forming part thereof.

Fig. 1 is a perspective view of an automobile defroster fan bracket showing my new design,

Fig. 2 is a side elevational view, and

Fig. 3 is an end elevational view.

I claim:

The ornamental design for an automobile defroster fan bracket, as shown.

WILLIAM W. WITTIE.
